UNITED STATES PATENT OFFICE.

CHARLES SHUBRICK SIMMONS, OF NORFOLK, VIRGINIA.

TOY.

1,337,570.

Specification of Letters Patent. Patented Apr. 20, 1920.

Application filed March 8, 1919. Serial No. 281,399.

To all whom it may concern:

Be it known that I, CHARLES S. SIMMONS, a citizen of the United States, residing at Norfolk, in the county of Norfolk and State 5 of Virginia, have invented certain new and useful Improvements in Toys, of which the following is a specification.

This invention relates to toys and has as its object to provide a toy which will be 10 automatic in its operation and will prove highly amusing. Also it is an object of the invention to provide a toy the use of which will entail a certain amount of construction work thus rendering the toy instructive as 15 well as amusing.

More specifically the object of the invention is to provide a toy which in its operation will simulate warfare as exemplified by an engagement between a tank and a fort.

20 In the accompanying drawings:

Figure 1 is a side elevation of the toy embodying the present invention, the track for the tank being broken away at intervals in its length;

25 Fig. 2 is a top plan view of the toy;

Fig. 3 is a vertical longitudinal sectional view through the fort constituting an element of the toy;

Fig. 4 is a bottom plan view of the top 30 of the tank;

Fig. 5 is a perspective view illustrating the several parts of the tank disassembled;

35 Fig. 6 is a vertical longitudinal sectional view through the gun which is to be mounted upon the tank;

Fig. 7 is a vertical transverse sectional view illustrating the manner of supporting the track for the tank.

Briefly stated, the invention consists essentially of a representation of a fort the parts 40 of which are loosely assembled so that when the fort is struck by a projectile its parts or walls will fall away, and a representation of a tank which is to travel down an inclined track or way in the direction of the fort and which likewise has its parts loosely assembled so that they will fall apart upon the tank being struck by a projectile, the fort and tank each embodying a spring

50 gun and means being provided for automatically firing the gun upon the tank as the tank reaches a predetermined point in its path of movement, other means being provided for automatically firing the gun 55 within the fort when the tank reaches another predetermined point in its path of

travel so that in the automatic operation of the toy the result of the engagement will be first the destruction of the fort and subsequently the destruction of the tank.

60

In the drawings the numeral 1 indicates a base upon which the fort is to be mounted and the numerals 2 and 3 indicate respectively the side and rear walls of the fort, the fort being open at its front. The said walls

65 2 and 3 may be in the nature of small wooden slabs and in setting up these walls, their lower edges are disposed in shallow grooves 4 formed in the upper face of the base 1, the rear wall 3 being disposed in

70 an inclined plane as also the side walls if found desirable although all of the said walls may be vertically disposed if desired.

The walls 2 and 3 are entirely disconnected from one another but these walls are main-

75 tained in set up position by the engagement of their upper edges in shallow grooves 5 formed in the under side of the top of the fort, which top is indicated by the numeral

6. It will be understood that the edges of 80 the side and rear walls of the fort are not to be snugly or tightly fitted in the grooves 4 and 5 formed in the base 1 and top 6 respectively, but that this engagement on the other hand is to be a loose one so that when

85 the projectile fired from the gun upon the tank strikes the fort, all of the walls will fall apart. Fixedly mounted upon the base

1 is a foundation block 7 for the fort gun, this block being housed within the fort

90 comprising the walls heretofore described when the said walls are properly set up and assembled. The gun for the fort is indicated in general by the numeral 8 and the same simulates a cannon and comprises

95 a barrel 9 which is suitably mounted upon the foundation block 7, the muzzle of the barrel projecting through the open front of the fort. The projectile which is to be

100 fired from the gun is indicated by the numeral 10 and is preferably in the nature of a short cylindrical rod of wood or other suitable material which is fitted into the bore 11 of the gun. At a point near its rear

105 end the projectile 10 is formed with a circumscribing groove 12 which, when the gun is loaded, registers with or is located opposite an opening 13 formed in the under

110 side of the barrel of the gun. A trigger indicated in general by the numeral 14 is pivotally mounted by a small eye member

115 upon the under side of the barrel of the

gun and this trigger may be formed from a suitable length of wire bent at the forward side of its pivot to form a detent 16 which projects upwardly through the opening 13 and engages in the groove 12 in the projectile 10 when the projectile is inserted into the bore of the gun. The trigger at the opposite or rear side of its pivot is bent to extend downwardly as indicated 10 by the numeral 17 and its lower end is engaged by or connected with the rear end of a rod 18 slidably mounted in suitable eye members 19 upon the upper side of the base 1. This rod extends longitudinally of the 15 base and beneath and forwardly beyond the muzzle on the gun 8 and at its forward end is provided with a small knob 20 which constitutes a buffer or abutment against which the tank, to be hereinafter described, 20 will strike when the tank reaches a point in close proximity to the fort. The projectile is to be fired from the gun by a coil spring 21 which is suitably arranged within the inner end of the bore 11 of the gun and 25 which spring is compressed when the projectile is fitted into the said bore, the inner or rear end of the projectile engaging the said spring, and the projectile in its loaded position having its forward end located substantially at the muzzle of the gun 30 barrel and restrained from discharge by the engagement of the detent 16 of the trigger 14 in the said groove 12. It will be evident at this point that when the rod 18 is thrust 35 rearwardly, the trigger 14 will be swung upon its pivot so as to disengage the detent 16 from the groove 12 whereupon the spring 21 will immediately act to discharge the projectile 10 from the barrel of the gun 40 in the direction of approach of the tank.

As before stated the tank is to travel along a track and this track is inclined so that the tank will travel by gravity down the said track in the direction of the fort. This 45 track may be of any desired construction but it preferably comprises two parallel rails 22 which may be of wood, metal, or any other suitable material or a combination of materials and which rails are provided at their upper sides and at their outer edges with upstanding flanges 23 so that the wheels of the tank will not pass off of the rails as the tank moves down the track. These rails at their lower ends are notched 50 as indicated by the numeral 24 so as to engage or interlock with suitable notches 25 formed in the forward corners of the base 1. The rails 23 are supported and held in spaced relation through the medium of a 55 suitable number of upright frames one of which is clearly shown in Fig. 7 of the drawings. Each of these frames comprises a pair of uprights or standards 26 connected by diagonal intersecting brace members 27, the standards 26 being provided at their

upper ends with small tenons or studs 28 which fit in suitable sockets 29 formed in the under sides of the rails 22. This construction, of course, permits of disassembly of the rails and their supports so that 70 the toy may be more conveniently packed, and it will be evident also that the rails at their lower ends may be disconnected from the base 1 for the same purpose.

The tank comprises a bottom 30 which 75 may be of wood or any suitable material and which is relatively heavy so that the tank as a whole will attain a desired speed in its travel downwardly along the track. Suitable wheels 31 are journaled in the under side of the bottom 30 of the tank and travel upon the rails 22. The side walls of the tank are indicated by the numeral 32 and the rear wall by the numeral 33, these walls corresponding respectively to the walls 80 2 and 3 of the fort heretofore described. As in the case of the fort, the side and rear walls of the tank are disposed at their lower edges in suitable grooves 34 formed in the upper side of the bottom 30 of the said tank 85 and these side and rear walls are supported in set up position by the engagement of their upper edges in grooves 35 formed in the under side of the top of the tank which top is indicated by the numeral 36. The 90 gun for the tank is illustrated in detail in Fig. 6 of the drawings and the same comprises, as in the instance of the gun for the fort, a barrel 37, a projectile 38, a propelling spring 39 for the projectile, and a trigger 40 pivotally mounted as at 41 upon the under side of the barrel and having an up-bent detent 42 at one side of its pivot fitting through an opening in the under side of the barrel and engaging in a circumscribing 100 groove 43 formed in the projectile 38. The trigger at the opposite side of its pivot is bent downwardly to provide a depending finger 44. The gun for the tank is mounted or stepped in a recess or socket 45 provided for its reception in the upper face of the bottom 30 of the tank, the finger 44 of the trigger extending downwardly through a slot 46 formed in the said bottom 30. This finger is of such length that it will project 110 beneath the bottom of the tank and to a position where it will strike a tripping element 47 in the nature of a pin or small rod arranged to extend between the rails of the track at any desired point in the length 115 of the track. Preferably the bottom 30 of the tank is provided with a tapered forwardly extending buffer portion 48 for engagement with the buffer or abutment 20 heretofore described.

The walls of the fort and tank having been assembled and the guns of the two having been loaded, the tank is disposed at the upper end of the inclined track and is then released. The tank will travel by grav- 130

ity down the said track and at a predetermined point in its movement the finger 44 of its gun will come into engagement with the element 47 resulting in the trigger being tripped whereupon the spring 39 will immediately discharge the projectile 38 from the gun in the direction of the fort. When the projectile strikes the fort the walls of the fort will collapse or fall apart, but the tank has not yet reached the lower end of the track. In the continued movement of the tank, its buffer portion 48 will strike the buffer 20 upon the rod 18 thus thrusting the rod in a rearward direction and tripping the trigger 14 of the fort gun whereupon the spring 21 of this gun will immediately discharge the projectile 10 in the direction of the tank and when the projectile strikes, the walls of the tank will fall apart.

Having thus described the invention, what is claimed as new is:

1. A toy comprising means forcibly discharging a projectile, a member movable in the direction of said means, and means in the path of movement of the said member for actuating the said means to discharge its projectile in the direction of the said member.

2. A toy comprising means forcibly discharging a projectile, a member movable by gravity in the direction of said means, and means in the path of movement of the said member for actuating the said means to discharge its projectile.

3. A toy comprising a projectile discharging device, a collapsible member movable in the direction of said device, and means in the path of movement of the said member for actuating the said device to discharge its projectile in the direction of the said collapsible member.

4. A toy comprising means forcibly discharging a projectile, an inclined track, a member movable down the track in the direction of the said means, and means in the path of movement of the said member for actuating the said means to discharge its projectile in the direction of the said member.

5. A toy comprising means forcibly discharging a projectile including a trigger, a member movable in the direction of said means, the said means being arranged to discharge in the direction of the said member, and an abutment element coacting with the trigger and arranged in the path of movement of the said member.

6. A toy comprising a projectile discharging device including a trigger, a member movable in the direction of said device, and

a slidably mounted rod coacting at one end with the trigger and having an abutment portion located in the path of movement of the said member.

7. A toy comprising a relatively stationary member, means forcibly discharging a projectile and movable in the direction of the said member, the said member being collapsible, and means in the path of movement of the projectile discharging means for actuating the same to discharge its projectile in the direction of the said member.

8. A toy comprising projectile discharging devices, one being relatively stationary and the other being movable in the direction of the first mentioned device, and means in the path of movement of the last-mentioned projectile discharging device for successively actuating both of said devices.

9. A toy comprising projectile discharging devices one movable in the direction of the other, and means in the path of movement of the movable device and actuated through movement of the said device to actuate both of said devices to discharge their respective projectile.

10. A toy comprising projectile discharging devices one of said devices being movable in the direction of the other, means arranged in the path of movement of the first mentioned device for actuating the same to discharge its projectile in the direction of the second mentioned device, and means also arranged in the path of movement of the first mentioned device for actuating the second mentioned device to discharge its projectile in the direction of the first mentioned device.

11. A toy comprising projectile discharging devices one movable in the direction of the other, means for actuating the first mentioned device to discharge its projectile at a predetermined point in its movement, and means actuated by the first mentioned device at another point in its movement to actuate the second mentioned device to discharge its projectile in the direction of the first mentioned device.

12. In a toy, a pair of collapsible members simulating fighting elements and each carrying projectile discharging means, and means whereby the force of gravity moves one of the members toward the other and having a trip operating one of said projectile discharging means whereby the projectile from one member impacts the other member causing collapse of both members.

In testimony whereof I affix my signature.

CHAS. SHUBRICK SIMMONS. [L. S.]
